UNITED STATES PATENT OFFICE.

CHARLES T. WITTSTEIN, OF CHICAGO, ILLINOIS, ASSIGNOR TO SCHRADER-WITTSTEIN COMPANY, OF CHICAGO, ILLINOIS, A CORPORATION OF ILLINOIS.

DESIGN FOR A SOLITAIRE-GEM-SETTING FINGER-RING.

SPECIFICATION forming part of Design No. 35,742, dated February 18, 1902.

Application filed August 7, 1901. Serial No. 71,274. Term of patent 14 years.

To all whom it may concern:

Be it known that I, CHARLES T. WITTSTEIN, a citizen of the United States, residing at Chicago, in the county of Cook and State of Illinois, have invented and produced a new and original Design for a Solitaire-Gem-Setting Finger-Ring, of which the following is a specification, reference being had to the accompanying drawings, forming a part thereof.

Figure 1 is a view in side elevation of a ring of my new and original design; Fig. 2, a view in edge elevation thereof, and Fig. 3 a plan view thereof.

As shown in the drawings, the leading or material feature of my design consists in the application of a rim-form bezel *a* and open-work *b*, supporting the same, to a solitaire-gem-setting finger-ring of the close-setting or so-called "gypsy-setting" type, the standards *c* of the open-work being of firm and substantial appearance and opposite sides of the open-work when viewed as indicated in Fig. 1 having a general outward and downward divergence, as indicated at the lines *c'*.

Minor features of my design are a trans-

verse perforation *d* in the open-work and having a curved lower wall, an intersecting perforation *d'* at right angles thereto, the walls of said perforations being completed by the rim-form bezel, a vertical perforation *d*² at 30 the vertical axis of the ring, and cuts or crevices *d*³ at the upper portion of the standards *c* and flanked by oppositely-curved scrolls or beads *d*⁴. As here shown, the sides *c* of the open-work are concaved or scalloped at *d*⁵, 35 and the lateral surfaces *d*⁶ of the open-work have a general downward and outward divergence.

Having described my invention, what I claim as new, and desire to secure by Letters 40 Patent, is—

The design for a solitaire-gem-setting finger-ring; as herein shown and described.

In testimony whereof I have signed my name to this specification in the presence of 45 two subscribing witnesses.

CHARLES T. WITTSTEIN.
